Application December 1, 1934, Serial No. 54,213

To all whom it may concern:

Be it known that I, Richard C. Zuckerwar, a citizen of the United States, residing at Gloversville, county of Fulton and State of New York, have invented a new, original, and ornamental Design for a Glove, of which the following is a specification, reference being had to the accompanying drawing, forming a part thereof in which—

Fig. 1 is a back view of the glove; and

The characteristic feature of the design resides in the arrangement of stitching, 3, 4, 5, of contrasting color to that of the body of the glove, which stitching extends from the base of the fingers to the wrist as shown in Fig. 1.

I claim:

The ornamental design for a glove as shown and described.
